US00D652036S

(12) **United States Design Patent**
Huang

(10) **Patent No.:** **US D652,036 S**
(45) **Date of Patent:** **** Jan. 10, 2012**

(54) **PASSIVE OPTICAL NETWORK GATEWAY**

(75) Inventor: **Chih-Hua Huang**, Shulin (TW)

(73) Assignee: **Askey Computer Corp.** (TW)

(**) Term: **14 Years**

(21) Appl. No.: **29/379,963**

(22) Filed: **Nov. 29, 2010**

(30) **Foreign Application Priority Data**

Oct. 29, 2010 (TW) 99305555

(51) **LOC (9) Cl.** **14-02**

(52) **U.S. Cl.** **D14/358; D14/240**

(58) **Field of Classification Search** D14/300-302,

D14/313, 314, 341, 348-370, 383, 385, 432,

D14/435, 436, 496, 125, 135, 137, 155, 240-242,

(57) **CLAIM**

The ornamental design for a passive optical network gateway, as shown and described.

DESCRIPTION

FIG. 1 is a perspective view of a passive optical network gateway showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.
